ATTY.

UNITED STATES PATENT OFFICE.

ARTHUR LABAN, OF MACKAY, QUEENSLAND, AUSTRALIA.

CINEMATOGRAPH-FILM SPOOL.

1,330,325.

Specification of Letters Patent. Patented Feb. 10, 1920.

Application filed September 27, 1918. Serial No. 255,977.

To all whom it may concern:

Be it known that I, ARTHUR LABAN, a subject of the King of Great Britain and Ireland, residing at Mackay, in the State of 5 Queensland and Commonwealth of Australia, have invented certain new and useful Improvements in Cinematograph-Film Spools; and do hereby declare the following to be a full, clear, and exact description of the invention, such as will enable others skilled in the art to which it appertains to make and use the same.

This invention relates to improvements in cinematograph film spools. The present 15 means of attaching the films to the spools, is, when the boss of the spool is made of wood, by placing the end of the film underneath a spring fixed to the boss and when made of metal such as thin tubing, by inserting 20 the end of the film into a slot formed in the boss then turning the spool around a few revolutions to insure film gripping, both these means are comparatively slow; there is also a great probability of scratching the 25 film or breaking off the end; the objects of this invention are to provide means for facilitating the mounting of films upon the spools, more especially when renewing same during operating, by which they may be instantaneously attached to and released from 30 the spools, also to eliminate the risk of damaging the films.

The invention consists in fixing on the wooden boss of a spool a sheet metal plate 35 provided with two rows of teeth by stamping same and spaced to correspond with the perforations (usually termed sprocket holes) on each side of the film; or inserting in the boss two rows of pins, screws, nails or such 40 like to serve as projections for engaging

with the perforations on each side of the film.

In spools having a sheet metal boss by fixing on same, by soldering or otherwise, a sheet metal plate as above described or 45 stamping the teeth out of the boss itself.

To fully describe the invention, reference is now made to the drawings in which:—

Figure 1, is a perspective view of the spool with one side partly removed to show the 50 boss.

Fig. 2, plan of detached toothed metal plate.

Fig. 3, end elevation of same.

Fig. 4, side elevation of same.

55

A and A' are the sides of the spool and B the wooden boss, C a toothed metal plate attached to the boss.

It has not been deemed necessary to illustrate by drawings the alternative method 60 of inserting pins, nails, screws or such like in the wooden boss, instead of employing a detachable toothed plate, nor to illustrate teeth stamped out of the boss when said boss is of tubular sheet metal.

65

In operation the end of the film is placed upon the toothed plate and one turn given to the spool when the film is instantaneously secured thereto and is instantaneously released when unwound without any risk of 70 damage.

What I do declare as my invention, and desire to secure by Letters Patent is:—

In combination with a hub for film reels, a plate secured to the hub, and outstruck 75 portions formed in the plate to provide projections for engagement with the perforations of a film.

In testimony whereof, I affix my signature.

ARTHUR LABAN.
